REMOVABLE SPACER

Nathan L. Herman, Cleveland, Ohio, assignor to Poe Machine and Engineering Company, Inc., New Wilmington, Pa.

Application May 10, 1949, Serial No. 92,446

1 Claim. (Cl. 85—51)

This invention relates to removable spacers, particularly to spacers adapted to be used on a shaft or spindle both ends of which are journaled in conventional support means and wherein the spacers can be removed without disengaging the journal means of the shaft.

The general object of the present invention is to provide a new and improved removable spacer which is characterized by the fact that it can be positively engaged with slitter discs or other means with which it is used and which can be engaged with or disengaged from engagement with a shaft without disturbing the end journal supports provided for the shaft.

Another object of the invention is to provide arcuate, removable spacer means wherein two or more of the spacers are normally used in end to end association to form an annular spacer unit.

A further object of the invention is to provide sturdy, inexpensive types of spacers of arcuate construction so that the spacers can be engaged with or removed from operative position on a shaft by merely loosening the assembly of elements carried by the shaft.

The foregoing and other objects and advantages of the invention will become more apparent as the specification proceeds.

For a better understanding of the present invention, attention is directed to the accompanying drawings which disclose one presently preferred embodiment of the principles of the present invention, and wherein:

Fig. 1 is an elevation, partially shown in longitudinal section, of a combination slitter disc and spacer means of the invention shown in operative association;

Fig. 2 is an enlarged longitudinal section, partially shown in exploded form, of a portion of the slitter and spacer means of Fig. 1;

Fig. 3 is an end or edge elevation of a spacer member of the invention; and

Fig. 4 is a vertical transverse section showing two spacer members in engagement with a positioning shaft.

With reference to the details of the structure shown in the drawings, a pair of parallel shafts or spindles 1 and 2 are provided. These shafts 1 and 2 are journaled at each end of each shaft by conventional means (not shown), or they are secured to suitable supports, as desired. In some instances, it may be desirable to use the removable spacers of the invention with other types of shafts which may have a cantilever support provided therefor but normally the spacers

of the invention have maximum application where both ends of the shafts 1 and 2 are secured to fixed devices. The shafts 1 and 2 both carry a plurality of slitter discs or members 3 in longitudinally spaced portions of the shafts. These slitter discs carried by the different shafts are arranged in cooperating positions on their mounting shafts whereby adjacent edges of each pair of slitter discs will be immediately adjacent each other to effect a cutting or slitting action on any material passed between the pairs of slitters 3.

As an important feature of the present invention, removable spacers 4 and 5 are carried by the shafts 1 and 2 intermediate the adjacent slitter members positioned thereon. These spacers 4 and 5 are of corresponding shape and construction only in this instance the spacers 5 are shown as being slightly narrower than the spacers 4. The spacers 4 and 5 are shown as being of arcuate form and in this instance are illustrated as comprising an arcuate length of approximately 180°, although the spacers may be of less than 180° in extent and they may have any desired width. Thus two of the spacers 4, or 5, can be positioned with the ends of the spacers in abutting relation to form an annular spacer unit. These spacers 4 and 5 are both provided with a pair of parallel, flat opposed side surfaces 6 and 7. These side surfaces of the spacers are adapted to be positioned flush against or abutted against the corresponding flat side surfaces formed on the slitters 3 so that a tight or compact assembly of spacers and slitters can be provided on the shafts 1 and 2.

In order to secure the assembly of spacers and slitters tightly to their positioning or mounting shafts, a shoulder 8 is provided on each of the shafts in most instances and the remaining end portion of the shafts 1 and 2 then are of reduced diameter from the shoulder 8 over to a point adjacent an opposite end portion of the shaft. The reduced diameter portion of the shafts 1 and 2 are provided with threaded portions 8a which have lock nuts 9 and 10 engaged therewith for exerting axial compressive forces on the assembly formed from the abutted slitters and spacer discs.

A special feature of the present invention is that the slitters 3 and the spacers 4 and 5 each have one or more pins 11 secured to and protruding or extending from one side surface thereof. These pins 11 are then received in recesses 12 that are shaped complementary to the protruding portion of the pins 11 and are properly

positioned circumferentially with relation to the slitter and spacer members so that the adjacent side surfaces of such members can be moved into tight contact with the pins snugly received in the recesses 12. It will be realized that the pins 11 may be of any desired shape and that any desired number of the pins may be provided. Usually the pins are carried on corresponding sides of each of the slitters and spacer member but in some instances it may be desirable to position the pins on both sides of certain members and to provide corresponding recesses in both surfaces of other members used in the assembly combination of the invention. By engaging pins 11 on the removable spacers with recesses 12 in abutted members, the engagement of the pins and recesses will serve to secure the spacers to the shaft with which such spacers are associated, as some of the spacers engage means carried by or formed in members such as the slitters 3 which are positively secured to the shafts.

In order to secure the slitters 3 and spacers 4 and 5 to the shafts 1 and 2, usually a longitudinally extending key 13 is carried by each of the shafts in a longitudinally extending recess 14 provided therein. Likewise, a similar recess 15 is provided in one spacer of each annular spacer unit so that the spacers will likewise be held in fixed position with relation to the shafts 1 and 2.

It will be seen that merely by loosening the lock nuts 9 and 10, then the associated slitter and spacer means of the invention can be loosened for slight axial movement on their positioning shafts 1 and 2. Hence any desired spacer member can be removed from the assembly, and new spacers be inserted therefor, or other re-arrangement may be made of the spacers positioned on the shafts 1 and 2.

While one complete embodiment of the invention has been disclosed herein, it will be ap-

preciated that modification of this particular embodiment of the invention may be resorted to without departing from the scope of the invention as defined by the appended claim.

Having thus described my invention, what I claim is:

A removable spacer assembly comprising a pair of flat surfaced uniform thickness semi-circular members of 180° in extent, said members being positioned with their ends abutted, protruding means on one side of said members, at least one of said members having a key receiving slot provided therein intermediate the ends thereof, said members having recessed means in the other side face thereof adapted to receive protruding means on an adjacent member when positioned thereagainst, said protruding means and said recessed means being accurately positioned circumferentially with relation to said key receiving slot to facilitate engaging protruding means on one pair of members with recessed means in any adjacent member.
